UNITED STATES PATENT OFFICE.

STEPHEN E. BABCOCK, OF TROY, NEW YORK, ASSIGNOR OF SEVEN-TWENTY-FOURTHS OF HIS RIGHT TO D. STEWART DENNISON, JESSE B. ANTHONY, AND THEODORE E. HASLEHURST, OF SAME PLACE.

JUNCTION SERVICE-BOX.

SPECIFICATION forming part of Letters Patent No. 225,546, dated March 16, 1880.

Application filed November 21, 1879.

To all whom it may concern:

Be it known that I, STEPHEN E. BABCOCK, of Troy, in the county of Rensselaer and State of New York, have invented certain new and useful Improvements in Junction Service-Boxes for Mains and Pipes for Conveying Steam and other Fluids, of which the following is a specification.

The object of my invention is to render said junction service-boxes of greater utility, and, while retaining all the qualities that fit the present style of said devices to the requirements of the expansion and contraction of the mains, to adapt each box for use as a valve for preventing the flow of steam through the service-box and its lateral pipes, while the current of steam passes uninterruptedly through the mains.

To this end my invention consists in combining with a junction service-box an adjustable sleeve so arranged as to be moved from the exterior of the box and operate as a valve within the box, as herein described.

In the accompanying drawings, which form a part of this specification, and to which reference is herein made, Figure 1 is a horizontal section at the line *xx* of my improved junction service-box; Fig. 2, a longitudinal section at the line *yy*; Fig. 3, a transverse section at the line *zz*, and Fig. 4 an end elevation.

As illustrated in the drawings, A is the exterior casing or box, cast of any suitable metal. On one of its outer sides a collar, *a*, is formed for receiving the fixed end *b* of the main B, which may be secured to said collar by means of a screw-thread or in any other suitable manner. Another collar, *a'*, formed within the box, has its bore coincident with that of the main B, and terminates in a valve-seat, *a²*, for the purpose hereinafter described.

Ranging in line with the center line of the main, and fixed to the box directly opposite to the collar *a'*, is a stuffing-box, *a³*, provided with a packing-gland, *a⁴*, arranged to compress the packing in the stuffing-box by forcing down said gland by means of nuts on the standing bolts *a⁵*. C, an adjustable sleeve that enters the box A through the stuffing-box *a³*. Its inner end, *c*, is reduced in diameter, so as to pass

into the opening of the collar *a'* and leave 50 an annular space for the emission of steam, and the capacity for such emission may be increased, when desired, by perforating the end *c* contiguously to its junction with the full diameter of the sleeve. A shoulder, *c'*, on the 55 sleeve is made to form a steam-tight joint (as a valve) with the valve-seat *a²*. At its outer end the sleeve C terminates in a stuffing-box, *c²*, which is provided with a packing-gland, *c³*, arranged to compress the packing contained 60 in said stuffing-box by means of the nuts on the gland-bolts *c⁴*.

The additional lugs *c⁵* on the stuffing-box *c²* are drilled to pass over the standing bolts *a⁵*, where they are engaged by the nuts *a⁶* and *a⁷*, 65 arranged on said bolts, to bear against the opposite faces of said lugs for the purpose of adjusting the sleeve endwise in either direction, as occasion requires.

The free end *d* of the main D enters the enlarged bore or chamber of the sleeve C through the stuffing-box *c²*, and, for the purpose of allowing for the endwise lengthening or "growth" by expansion, ample space should be allowed between the end of the main and the end of 75 the chamber of the sleeve. E, lateral or service pipes. These may be connected to the box A, either by means of stuffing-boxes, as at *e*, or by being screwed into the box, as at *e'*. F, the cover or "bonnet" of the box A, to which it 80 is secured so as to form a steam-tight joint by means of the bolts *f*.

The junction-boxes should be properly secured in position at such points on the line of mains as may be selected for permanent stations or starting-points, from which the expansion of each section of the main shall commence. The mains should then be connected with the boxes by screwing or otherwise securing the fixed end *b* of each section to its proper place, 85 and by inserting the free end *d* of the next section into its place in the sleeve C, as herein-before described.

When the mains are connected and the junction-box is not to be used as a feeder for the 95 lateral pipes, or when from any cause it is necessary to obtain access to the interior of the junction-box while steam is in the mains, the

sleeve C should be moved inwardly until the shoulder c' is brought into steam-tight contact with the valve-seat a^2 . This end is accomplished by "slackening off" the nuts a^6 , which bear beneath the lugs c^5 , and screwing down the nuts a^7 above said lugs.

By bringing the valve-seat a^2 and sleeve C into contact, as above described, and as shown in Fig. 2, a continuous pipe is formed, through 10 which the steam may flow without entering the chamber of the box A. When the junction-box is to be used as a service-box for feeding the lateral pipes, the sleeve C should be retracted, as shown in Fig. 1, to leave the space 15 required for the admission of steam into the chamber of the box A, from whence the steam passes into the lateral pipes E.

By means of the nuts a^6 and a^7 the position of the sleeve C can be accurately adjusted at 20 any point required for regulating the volume of steam discharged from between the valve-seat a^2 and shoulder c' .

I claim as my invention—

1. The combination, with the box A, adapted to receive the fixed end b of a main or pipe, 25 and provided with a stuffing-box, a^3 , as herein described, of the adjustable sleeve C, fitted to receive the free end d of a main or pipe, said sleeve being arranged to adjust from the exterior of the box A, and adapted to be operated 30 at pleasure either as a governing-valve or as a pipe for connecting continuously the sections of the mains, as herein specified.

2. The combination, with the box A, provided with a valve-seat, a^2 , and stuffing-box 35 a^3 , of the adjustable sleeve C, provided with the shoulder c' and stuffing-box c^5 , all constructed and arranged to operate essentially as herein specified.

STEPHEN E. BABCOCK.
